Atty.

UNITED STATES PATENT OFFICE

ALLAN CHENEY, OF MELROSE, MASSACHUSETTS, ASSIGNOR TO THE CHENEY COMPANY, OF WINCHESTER, MASSACHUSETTS, A CORPORATION OF MASSACHUSETTS

INTERLOCKING METAL FLASHING

Application filed January 2, 1929. Serial No. 329,705.

This invention relates to improvements in interlocking metal flashing and has for its object to provide a flashing preferably constructed of sheet metal and pressed in such form 5 that when it is interposed between two courses in masonry in conjunction with the usual layer of mortar which is employed as a binding agent, that a perfect mechanical bond will be provided in every direction between 10 the flashing and the adjacent courses of masonry.

Another object of the invention is to so construct the strips of flashing that they may be effectively interlocked one with another without it being necessary to solder said strips together, there being an end portion provided upon each strip, which, when the strips are connected together will underlie the adjacent end portion of the strip to which it is connected 20 in such a manner that if water seeps between the interlocked strips that this water cannot pass downwardly through the masonry, but will, on the other hand, be diverted to the exterior faces of the wall at a point 25 where it can do no damage.

Still another object of the invention is to provide a flashing strip with a flange projecting laterally from a face thereof and extending along a side thereof, the metal of said flange being folded in a manner to reinforce and stiffen the flange.

The invention consists in an improved construction of flashing as set forth in the following specification and particularly as pointed out in the claims thereof.

Referring to the drawings:

Figure 1 represents a perspective view of a strip of flashing embodying my invention, the 40 central portion of the strip being broken away to save space in the drawings.

Fig. 2 is an enlarged vertical section as taken on the line 2—2 of Fig. 1, illustrating two strips of flashing interlocked together and 45 inserted in a layer of mortar between two courses of masonry.

Fig. 3 is an enlarged horizontal section taken on the line 3—3 of Fig. 1.

Fig. 4 is a transverse section through the 50 wall of a building illustrating two of the

uses to which my improved flashing may be put in the wall of a building.

Like numerals refer to like parts throughout the several views of the drawings.

In the drawings, 5 represents a strip of 55 flashing preferably constructed of sheet metal and folded to provide grooves 6 and ridges 7 alternately arranged upon both sides of the strip. The grooves and ridges are, furthermore, formed with side walls 8 which are 60 common to both the grooves and ridges and said walls are inclined to both of the faces of the flashing material in a manner to form dove-tail shaped grooves and ridges. The side walls 8, furthermore, of both grooves and 65 ridges taper longitudinally of said grooves and ridges toward an edge of the material and preferably the opposite sides of a groove on one face of the strip tapers in the opposite direction to that in which the opposite sides 70 of the adjacent groove which is located upon the same face of the strip tapers.

The grooves, furthermore, on each side have their alternate edges parallel and the remaining edges are inclined alternately in opposite 75 directions.

The strip of flashing 5 has a downwardly bent flange 9 at one end thereof, said flange being inclined inwardly at an acute angle to the under surface of said strip. At its other 80 end the strip 5 has an upwardly and inwardly bent flange 10 which is located at an acute angle to the upper surface of said strip. The portion of the strip 5 between the flange 10 and the adjacent groove 6 slopes upwardly 85 from the bottom of said flange 10 to the top of the groove, thereby providing an inclined face 11 and forming a water deflecting trough.

The strip 5 is bent lengthwise thereof and 90 at one side thereof at 12 to form a flange 13, and the ridge portions 7 are flattened where they extend across the flange 13 so that the side walls 8 of the grooves and ridges are pressed against the bottoms of the grooves, 95 thereby forming plaits 14 across the flange. The plaits 14 reinforce and stiffen the flange 13.

In Figs. 2 and 4 the strip 5 as illustrated in position in a layer of mortar 15 between 100

courses of bricks 16, and in Fig. 2 the end portions of two strips of flashing are shown interlocked together, at which time the flange 9 of one strip interlocks with the side wall 8 of the groove 6 of another strip and the inclined face 11 of the latter strip is located beneath the under surface of the former strip. When two strips of flashing are secured together in this manner it is not necessary to solder said strips together, and if water does seep between the adjacent surfaces of the flange 9 and wall 8, this water will run down the inclined surface 11 to the bottom of the flange 10 and be diverted toward the exterior faces of the wall. 10 The strip 5 of flashing is preferably slightly less in width than the width of the wall in which it is employed in order that the mortar in which the strip is imbedded may be pointed in the usual well known manner. 15 When utilized at any of the locations in the wall of a building where flashing material is generally employed, the flashing of this invention will prevent water which may have found its way between the courses of masonry located thereabove from seeping downwardly into the courses of masonry located therebeneath. 20 By providing the alternate grooves 6 and ridges 7 and by tapering said grooves and ridges as illustrated it is possible to imbed the strip of flashing in the mortar 15 between the two courses of masonry and provide a perfect bond between the flashing and the mortar upon each side thereof and also between the adjacent courses of masonry between which the flashing strip is located. 30 At certain locations upon the wall of a building, as, for example, beneath a coping, it is not necessary to have the laterally projecting flange 13 formed upon the strips of flashing that are employed. At other points, however, it is desirable to have the flashing inserted between courses of masonry with a flange 13 projecting either upwardly or downwardly. In the construction illustrated at A in Fig. 4, the flange 13 projects downwardly outside of a base flashing 17 which projects upwardly from the roof (not shown in the drawings) of a building. 40 The construction illustrated at B, Fig. 4, is utilized in a wall at a point below the roof and in such instances the flashing is inserted between the layers of masonry with the flange 13 projecting upwardly against the inner surface of the wall. The upwardly projecting flange prevents water from working inwardly beyond said flange and doing damage upon the interior of the building. In all instances where the flange 13 is formed upon the strip of flashing, the plaits 14 reinforce and stiffen the flange and after the flashing has been inserted in the masonry, the flange may be sprung outwardly, as, for 55 example, in order that a base flashing may

be inserted thereunder, and when the flange is again forced rearwardly against the front face of the base flashing, the rear surface of the flange will remain in close contact with the base flashing and there will not be a tendency for the flange to spring outwardly from the front face of the base flashing. 70

I claim:

1. A flashing consisting of a continuous strip of sheet metal bent to form dove-tail shaped corrugations and a flange projecting laterally from the face of said strip at a side thereof, said corrugations being flattened against the face of said strip and extending transversely across said flange and reinforcing the latter. 75

2. A flashing consisting of a continuous strip of sheet metal bent to form dove-tail shaped grooves and ridges and a flange projecting laterally from a face of said strip at a side thereof, said ridges being flattened against the face of said strip and forming plaits extending transversely across said flange whereby the latter is reinforced. 80

3. A flashing consisting of a continuous strip of sheet metal bent to form dove-tail shaped grooves and ridges, a downwardly bent flange at one end of said strip and an upwardly bent flange at the other end of said strip, the end portion of the strip between said last-named flange and the adjacent groove sloping downwardly toward said flange and forming a water deflecting trough. 90

4. A flashing consisting of a continuous strip of sheet metal bent to form dove-tail shaped grooves and ridges, a downwardly bent flange at one end of said strip and an upwardly bent flange at the other end of said strip, the end portion of the strip between said last-named flange and the adjacent groove sloping downwardly from the top of the groove to the bottom of said flange and forming a water deflecting trough. 100

5. A flashing consisting of a continuous strip of sheet metal bent to form dove-tail shaped grooves and ridges, a downwardly bent flange at one end of said strip, an upwardly bent flange at the other end of said strip, the end portion of the strip between said last-named flange and the adjacent groove sloping downwardly toward said flange, a side flange projecting laterally from a face of said strip and plaits extending across said side flange and reinforcing the latter. 115

In testimony whereof I have hereunto set my hand.

ALLAN CHENEY.
